UNITED STATES PATENT OFFICE.

ISIDORE STARR, OF NEW YORK, N. Y.

REVOLVING-PICTURE FRAME.

Application filed March 29, 1922. Serial No. 547,722.

To all whom it may concern:

Be it known that I, ISIDORE STARR, a citizen of the United States, and a resident of the city of New York, borough of Bronx, 5 in the county of Bronx and State of New York, have invented a new and Improved Revolving-Picture Frame, of which the following is a full, clear, and exact description.

10 This invention relates to improvements in picture frames, an object of the invention being to provide a frame open at both sides to expose two pictures and mounted for turning movement to expose either of 15 the pictures.

The invention further contemplates the provision of a distinctly novel form of base upon which any conventional type of frame may be mounted for rotation.

20 A further object is to provide a device of this character which will be neat and attractive in appearance, simple and practical in construction, serviceable in use, and which will lend itself to economical manufacture.

With these and other objects in view, the invention consists in certain novel features of construction and combinations and arrangements of parts as will be more fully 30 hereinafter described and pointed out in the claims.

In the accompanying drawings:

Figure 1 is a view in front elevation of my improved frame and support; and 35 Figure 2 is a view in longitudinal section therethrough.

Referring in detail to the drawings, I have used the reference numeral 1 to designate a base preferably formed of metal or 40 some other material sufficiently heavy to counterbalance the weight of a picture frame which may be supported thereby. A circular plate 2 is provided with an annular depending flange 3 fitting within an annular 45 groove 4 in the upper face of the base 1. Grooves 5 and 6 in the under face of the plate and the upper face of the base respectively cooperate to form a ball race wherein ball bearings 7 are located, said 50 bearings providing rotary mounting for the plate 2 upon the base 1.

A pocket or recess 8 is provided in the under face of the base 1 and a central depending stud 9 carried by the plate 2 extends through an opening 10 in the base and into the pocket 8. Locking nuts 11 are

screwed onto the lower threaded end of the stud 9 and serve to hold in place a bearing cone 12 supporting ball bearings 13 which ride in a groove 14 in the recessed portion 60 of the base. By virtue of the construction above described the plate 2 and its associated cone 11 have a double anti-friction connection to facilitate the rotation of the plate upon the base. 65

A diametrically extending sleeve 15 is carried by and preferably integral with the plate 2. A pintle 16 extends through the sleeve. A pair of substantially U shaped brackets 17 are formed with bearing sleeves 70 18 at their lower intermediate portions, these sleeves being accommodated in openings 19 in the main sleeve 15 and receiving the pintle, whereby to provide partial pivotal mounting of the brackets on the 75 pintle. The upstanding arms of the brackets 17 are adapted to receive and embrace the lower side of a picture frame, designated by the reference numeral 20, and the pivotal movement of the brackets is limited in each 80 direction by angular shoulders 21 integral therewith and engageable with the upper face of the base plate as the brackets are pivoted.

It will of course be apparent that the construction above described is suitable for supporting any conventional type of picture frame, but I prefer to use a special kind of frame with the rotary base so that two pictures may be conveniently displayed and the 90 brackets may be tilted in either direction to incline the frame for the better exposition of either picture. The frame 20 further includes four channeled sides, and a portion 24 of the upper frame section is pivoted, as 95 indicated at 21, the free end of said pivoted section being normally locked by a spring catch 22 and a stud 23 fixed to the outer face of the frame. The section 24 may be swung upwardly, as indicated in dotted lines 100 in Figure 1, to permit the insertion of a pair of glass plates 25 into the frame, between which a picture or pictures 26 may be inserted for exposition through either side of the frame. The frame may be tilted in 105 either direction upon the brackets, as indicated in dotted lines in Figure 2 to better expose either of the pictures, or either side of the picture in the frame.

With particular reference to Figure 1 of 110 the drawings, it is to be noted that by making only a portion of the upper side of the

frame in the form of a hinged section, a strengthening cross bar 27 is provided which prevents the accidental bending or distortion of the frame 20 while the glass plates 5 and the pictures are being inserted therein.

Although I have illustrated one of the preferred embodiments of my invention, it will be obvious that numerous slight changes and alterations might be made in the general 10 form and arrangement of the parts described without departing from the invention, and hence I do not wish to limit myself to the precise details set forth, but shall consider myself at liberty to make such 15 slight changes and alterations as fairly fall within the spirit and scope of the appended claims.

I claim:

1. The combination with a picture frame 20 including transparent picture exposing panels on the opposite faces thereof, of means for supporting said frame for rotation at its lower end, and for limited rocking movement to dispose the same at opposite inclinations.
2. The combination with a picture frame including transparent picture exposing panels on the opposite faces thereof, of means for supporting said frame for rotation at its lower end, and for limited rocking movement to dispose the same at opposite inclinations.

tions, said means comprising a base having a stationary section and a superposed rotary section and a hinged connection between the lower end of the frame and the rotary section, and stop elements formed on the hinged connection and engageable with the base for limiting the swinging movement of the frame in opposite directions whereby to support the same at opposite inclinations. 35

3. As a new article of manufacture, a picture frame including front and rear transparent picture exposing faces, and means for supporting the frame at its lower end for rotation and limited horizontal rocking 40 movement to dispose the same at opposite inclinations when rotated.

4. In a device of the character described, a base, a plate mounted to rotate on the base, a picture frame carried by the plate, 50 said frame mounted for limited pivotal movement on the base, and including two transparent picture exposing faces.

5. The combination with a supporting base, of a pair of substantially U shaped 55 brackets pivoted on the base and adapted to support a picture frame, and shoulders on the brackets engageable with the base to limit the pivotal movement of the brackets and support the frame in inclined position. 60

ISIDORE STARR.
